UNITED STATES PATENT OFFICE.

EDMOND W. T. RICHMOND, OF ROMFORD, ENGLAND.

DESIGN FOR A GAS-STOVE.

SPECIFICATION forming part of Design No. 33,879, dated January 8, 1901.

Application filed December 11, 1900. Serial No. 39,559. Term of patent 7 years.

To all whom it may concern:

Be it known that I, EDMOND WALTER TYRRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a perspective view of a gas-stove embodying my design.

The leading features of my design are the rectangular body portion A, having the smooth top a, on which is supported by stands b a frame B, containing a series of parallel cross-bars b', the central top front portion C, having a series of parallel vertical openings c, the two rectangular openings D,

below the portion C, divided by a panel d, and the drawers E, at the bottom of the openings, having the knobs or handles e.

The cross-bars b' are wavy or zigzag in contour, and at the front of the body portion there is a front rail or pipe F. At the top of the body portion and at the back end thereof there are two upwardly-projecting cylindrical portions H.

I claim—

The design for a gas-stove, substantially as herein shown and described.

In testimony whereof I have hereunto subscribed my name.

EDMOND W. T. RICHMOND.

Witnesses:

KATHARINE MACMAHON,
EDWARD C. DAVIDSON.
